G. HILGER

REFRIGERATION SYSTEM

Filed Nov. 22, 1924

Inventor:
George Hilger
B. G. Hindle & Parker & Co., Atty's.

UNITED STATES PATENT OFFICE.

GEORGE HILGER, OF CHICAGO, ILLINOIS.

REFRIGERATION SYSTEM.

Application filed November 22, 1924. Serial No. 751,449.

In certain of its aspects, my invention pertains to a refrigeration system employing one or more expansion elements or coils, in combination with a control valve operable 5 automatically under the control of the temperature of the refrigerant returning to the compressor, to regulate the flow of refrigerant to the expansion element; and one of the objects of the invention is to provide, in 10 conjunction with such a temperature responsive valve, an automatic pressure reducing valve operating to supply to the temperature responsive valve refrigerant at a reduced substantially constant pressure, whereby to 15 render the temperature responsive valve sensitive to relatively slight changes in the temperature of the returning gas.

The invention also has special reference to a refrigeration system of the type having 20 a plurality of refrigerating units which it is desirable to control independently; and a further object of my invention is to provide automatic means for maintaining such units at all times at maximum efficiency, in combination with means also operating automatically to maintain a supply of refrigerant for the several units, at a predetermined pressure, sufficient only to meet the requirements at any given time, thus effecting a reduction in the amount of the refrigerant 30 consumed and a consequent saving of power in the operation of the refrigerating machine.

A further object of my invention is to provide an improved refrigeration system in 35 which any one of a plurality of refrigeration units may be controlled independently of and without disturbing the operation of the other units, either manually or automatically.

Another object is to provide a system in 40 which any one of several refrigerating units may be defrosted independently, without disturbing the operation of the other units, and in a manner such as to reduce the condenser pressure with a corresponding reduction 45 in the power consumed.

Still another object is to provide in a refrigeration system means whereby any one of a plurality of refrigerating units may be 50 pumped out or exhausted of the refrigerant independently of the other units, to permit of the making of repairs and the like.

In the preferred embodiment of my invention illustrated, I employ a system of 55 headers one connected with the discharge

side of a compressor, another connected with the suction side of the compressor and a third header adapted to be connected with either the discharge or suction sides of the compressor. A pressure operated expansion 60 valve of ordinary or preferred construction operates to maintain in the first or charging header a predetermined pressure, and the flow of refrigerant to each of the several refrigerating units from said charging 65 header is under the control of a valve governed by the temperature of the refrigerant returning from the given unit to the second or suction header. The third or combination defrosting and pumping-out header is 70 in valve-controlled communication with the return side of each of the refrigerating units and is arranged to be connected under the control of suitable valves either with the discharge side of the compressor for defrosting 75 purposes or with the suction side of the compressor for pumping-out purposes. The automatic temperature controlled valve for each of the units is of the general character described and claimed in my copending application Serial No. 737,455.

In the accompanying drawings, Figure 1 is a fragmentary perspective view partially diagrammatic in character of a refrigeration system embodying my invention.

Fig. 2 is a fragmentary vertical sectional view through a pressure-operated expansion valve of preferred construction.

Fig. 3 is a similar view through the temperature controlled valve employed for each 90 of the refrigerating units.

The system in its preferred form comprises a compressor A of a suitable character, a condenser B and a liquid receiver C. The compressor has a discharge pipe 4 with 95 which is connected a pipe 5 leading to the condenser. The condenser in turn is connected by a pipe 6 with the liquid receiver, and the latter is connected by a pipe 7 with a pipe 8 of relatively large size constituting 100 the charging header. The pipe 7 has a hand operated valve 9 interposed therein and also an automatic primary expansion valve 10, the latter being interposed between the valve 9 and the header. This valve 10, shown in 105 detail in Fig. 2, may be of any suitable construction, being under the control of the pressure at the discharge side of the valve so as to maintain the latter substantially constant. It comprises briefly, in the present 110

2
instance, a casing 11 having at its upper portion a through passageway controlled by a valve member 12. The valve member is connected with a diaphragm 13, and a coiled 5 expansion spring 14 enclosed in the lower portion of the casing maintains a predetermined pressure on the diaphragm which is counterbalanced by the pressure on the discharge side of the valve. By adjusting the 10 spring tension the pressure on the discharge side of the valve and in the present instance in the header 8 may be readily varied.

I have herein shown diagrammatically three rooms or chambers R, R' and R'' each 15 containing a refrigerator unit or coil 15, the lower end of which is connected by a pipe 17 with the charging header 8 and the upper end of which is connected by a pipe 18 with a large pipe 19. The latter is connected by 20 a pipe 20 with the suction side of the compressor and constitutes the suction header of the system.

The supply pipe 17 for each of the coils 15 is provided with suitable valve means 25 whereby the unit may be cut out of the system at will. Herein I have shown a simple hand operated valve 21 in each of said pipes for this purpose.

The primary expansion valve 10 serves 30 to maintain in the charging header 8 a supply of refrigerant at a predetermined pressure sufficient to meet the requirements of the several units, this pressure being determined by the lowest temperature which 35 it is desired to maintain in any one of the rooms or chambers. To control the flow of refrigerant through the several units from the charging header in a manner such as to supply that volume of refrigerant only 40 which the unit is capable of evaporating, I provide an automatically operating valve generally designated by the numeral 23. This valve is of the character shown in detail in Fig. 3, being so constructed as to 45 operate to check the flow of refrigerant to the coil when the temperature of the refrigerant at the discharge end of the coil falls below a predetermined point.

Preferably the valve comprises a casing 24 50 having in its upper portion a through passageway controlled by a valve 25, which passageway is connected in the pipe line 17 leading to the coil. The lower portion of the casing is constructed to provide a jacket 55 26 interposed in the pipe line 18 connected with the return side of the coil. The jacket 26 partially surrounds a chamber 27 in the casing, one wall of said chamber being formed by an insulating diaphragm 28 operatively associated with the valve 25. In the 60 chamber 27 is contained a quantity of ammonia or the like, which being subjected to the temperature of the refrigerant leading from the coil exerts a greater or less pressure on the diaphragm 28 tending to open

the valve 25 against the pressure of the refrigerant in the feed pipe 17 plus the action of a spring tensioning means generally designated 29. By adjusting the spring tension the pressure of the ammonia in the chamber 27 at which the valve 25 will close its passageway may be readily determined so as to supply to the coil only that volume of refrigerant which it is capable of evaporating. Thus when the coil is entirely 70 frosted the temperature of the refrigerant passing through the jacket 26 effects a sufficient reduction of pressure in the chamber 75 27 to check the flow of refrigerant to the coil preventing a freezing back to the compressor. 80

It will be seen that the gas in the chamber 27 is not influenced by the temperature of the refrigerant in the upper portion of the casing due to the presence of the insulation 85 in the diaphragm 28. This is of vital importance for the reason that the valve in order to be operative must be set to operate under a fixed temperature difference between the temperature and pressure of the 90 refrigerant passing to the coils and the temperature of the refrigerant returning from the coils, and if subjected to variable disturbing influences such as the temperature of the chamber being cooled or the temperature of the refrigerant passing to the coils, the valve will obviously fail to operate as intended. 95

Also, it is to be noted that the chamber 27 is independent of the pressure of the refrigerant returning to the compressor and passing through the jacket 26. Consequently the expansion element in the chamber 27 is governed solely by the temperature of the refrigerant passing through the 100 jacket. Also variations in the temperature of the returning refrigerant are transmitted to the expansion element in the chamber 27 only gradually due to the time interval required for the transmission of heat 105 through the wall of the chamber 27. This is essential for the reason that a sudden increase of pressure in the chamber 27 due to the passage of superheated gas through the jacket 26 would serve to open the valve 25 110 and allow the passage of more refrigerant to the coil than the coil could evaporate. In other words, it would result in the flooding of the system, with an attendant waste. By retarding the operation of the valve it 115 is enabled to control the flow of refrigerant to the coil in accordance with the volume which it is capable of evaporating. 120

It will be observed that the operation of any of the valves 23 to cut off one or more 125 of the coils 15 reacts upon the pressure in the charging header 8 so as to operate the valve 10 so that the predetermined pressure in the charging header is maintained. An important advantage is gained as a result 130

of the maintenance in the charging header of this reduced pressure as distinguished from condenser pressure which not only varies as the temperature of the cooling water 5 employed in the condenser varies, but is normally so high as to render the temperature responsive valve impractical. Thus, with a condenser pressure of from 150 to 200 pounds, this pressure applied to the top 10 of the valve member would necessitate the production in the thermal chamber of the valve of a correspondingly high pressure to open the valve. As a result, as soon as the pressure in the thermal chamber had over- 15 come the pressure on the top of the valve so as to lift the valve slightly, the condenser pressure passing around the valve, and so admitted to its under side, would cause the valve to move suddenly into a wide open position. Thus, it will be seen 20 the valve will operate with a jerky hammer-like action. Moreover, such movement of the valve member into wide open position would admit refrigerant at condenser pressure 25 to the coil, at a much higher rate than the refrigerant is capable of evaporating, and heavily saturated refrigerant would be returned to the compressor before the pressure in the thermal chamber could be reduced sufficiently to check it. On the other 30 hand, by reducing substantially the pressure supplied to the temperature responsive valve the difference in pressures operating the valve is relatively small so that the latter is very sensitive and effective to control the flow of refrigerant as intended.

The normal operation of the system involving a plurality of coils or other expansion elements is as follows: Assuming that 35 it is desired to maintain the several rooms R, R', and R'' at varying temperatures, the expansion valve 10 is adjusted to maintain a pressure in the charging header 8 such that the temperature thereof is somewhat 40 below the lowest temperature which it is desired to maintain in any of the rooms. The valves 21 leading to the several units being open, refrigerant is supplied simultaneously to all of the coils. As soon as any 45 one of the coils becomes entirely frosted and reaches a condition such that it is evaporating the maximum amount of refrigerant of which it is capable, a reduction in pressure occurs in the chamber 27 of the valve, 50 which checks the flow of refrigerant to the coil feeding only that volume which will maintain the coil operating efficiently. When the desired room temperature has 55 been reached, the operator closes the proper valve 21. The other coils, however, continue to operate undisturbed by the cutting off of the one coil until finally the desired room temperatures are obtained in their respective chambers when they too are cut off by 60 the operation of their valves 21. In any case

the decrease in the volume of the refrigerant consumed reduces the amount of work required to be performed by the refrigerating machine.

It will be understood that by adjusting 70 the pressure and temperature of the refrigerant in the charging header in accordance with but slightly below the lowest temperature to be attained in any room, the valve in this case will operate just as in the case of 75 the other rooms because then the temperature of the returning refrigerant, even though the same as the room temperature, will be higher than the temperature of the refrigerant entering the coil. 80

Furthermore such adjustment of pressure in the charging header will insure that the pressure of the refrigerant returning to the compressor from the coil of a room to be maintained at a relatively high temperature, 85 will not be higher than the pressure required to cool the coldest room and hence not high enough to enter its coil from the return side after passing from the coil of the high temperature room. For example a condition 90 frequently met with in practice, is that where several rooms must be maintained at varying degrees of temperature. Thus for the sake of illustration, it may be assumed that it is desired to maintain chamber R'' 95 at a temperature of 30°; room R' at a temperature of 20°; and room R at a temperature of 10°, and that these temperatures have risen slightly in each case so that the rooms require further refrigeration. Now 100 if the refrigerant were supplied to the valve 23 of each of said rooms at a pressure higher than that required for 10° (the temperature of the coldest room R) the pressure discharged from the coil of room R'' of highest temperature would be so high as to be capable of entering the coil of room R. Since the temperature of this room is relatively lower, the refrigerant entering this coil would condense and collect in the coil. Then when room R'' had been reduced to 105 the predetermined temperature of 30° and its valve 23 closed, pressure entering the coil of room R would forcibly discharge the condensed refrigerant therein back to the compressor with the result that considerable damage would result to the compressor such as knocking out the head. On the other hand it will be seen that by the provision of the regulating valve 10 adjusted 110 with regard to the temperature of the coldest room such an occurrence could not take place.

Thus, the valve 10 operates to maintain a supply of refrigerant at a proper predetermined pressure available to each of the refrigerating coils or units, and the valves 23 operate to insure that the individual coils shall be maintained at all times at their maximum efficiency, feeding the maximum 115 120 125 130

amount of refrigerant which can be evaporated and no more. At the same time each of the refrigerating units is independent of the other units and the cutting off of any one of the units effects a corresponding saving in the amount of power consumed at the compressor.

The use of an expansion or reducing valve in combination with a control valve for each coil is advantageous because a sudden or sharp reduction in pressure such as would be effected by the use of a single valve would result in a wire drawing of the refrigerant which is objectionable because of an attendant cutting action on the valve and its seats producing excessive wear and requiring frequent repairs. With applicant's arrangement the expansion valve operates to reduce the pressure only partially, while the control valve effects a further pressure reduction as determined by the requirements of the system. Consequently neither valve is required to make sharp pressure reductions as is necessary when only one valve is used.

Still another advantage is that a constant pressure maintained in the charging header renders it unnecessary from time to time to reset the valve 23. The condenser pressure varies with changes in the season because the temperature of the cooling water employed for the condenser correspondingly changes. The valve 10 insures that the pressure in the charging header shall be independent of or unaffected by changes in the condenser pressure.

The system thus far described lends itself readily to the use of a third header for purposes of defrosting any one or more of the refrigerating units without interrupting the operation of the system as a whole or for the purpose of pumping out or exhausting one or more of the units. This third header is also in the form of a pipe designated 30 and herein shown as extending parallel to the pipes 8 and 19 constituting the charging and suction headers. This pipe 30 is connected with each of the return pipes 18 through the medium of a hand operated three-way valve 31. Also it is adapted to be connected with either the discharge or suction sides of the compressor by means of a pipe 32 having branches 33 and 34 respectively connected with the discharge and suction lines 5 and 20. A hand operated valve 35 is adapted to control communication between the discharge side of the compressor and the pipe 30, and a hand operated three-way valve 36 selectively controls communication between the suction side of the compressor and either the pipe 32 or the suction line 20.

It frequently happens that the refrigerating coils become coated with layers of snow and ice which serve as insulators prevent-

ing the absorption of heat from the room being cooled by the evaporating refrigerant in the coil. This is especially true when the room is used for cooling products having a tendency to give off vapor when placed in the cooling room. As a result it becomes necessary to remove the coating of ice or snow as the case may be and the method commonly employed is to strike the coil with a suitable implement cracking off the ice and allowing it to fall to the floor. This ice has thus been the cause of considerable annoyance and moreover is a source of waste not only from the standpoint of the power consumed in producing it but also because it reduces the efficiency of the system. By means of the construction and arrangement which I have provided it is possible to effect the removal of the ice by passing the refrigerant directly from the compressor and hence in a heated state to the coil. This is accomplished without disturbing the normal operation of the other coil by opening the valve 35 so as to allow a portion of the refrigerant discharged from the compressor to pass directly into the header 30 and into the pipe 18, the valve 31 having been operated to open communication between this pipe and the header 30 and incidentally to cut off communication between the pipe 18 and the suction header 19.

The hot refrigerant passing directly from the compressor to the pipe 18 and through the valve jacket 26 quickly causes the valve 23 to open. Further, the valve 21 in the pipe 17 is left open so that the refrigerant passes through the refrigerating coil, the supply pipe 17 and into the charging header 8. Owing to the presence of the valve 10 the pressure in the charging header is substantially less than the pressure in the pipe 18 now connected directly with the compressor and the cutting out one of the coils from refrigeration reacts upon the valve 10 so that the latter operates to maintain in the charging header the predetermined constant pressure. It will be observed that in such passage of this portion of the refrigerant through the coil 15, not only is the ice on the coil melted, but in so melting it cools the refrigerant rendering it unnecessary to pass the refrigerant through the condenser. This effects a reduction in the condenser pressure with a consequent saving in the power consumed during the defrosting operation.

In the event that one of the coils is in need of repair or for any other reason it is desired to exhaust it, this may be accomplished by connecting the return pipe 18 for that coil with the suction side of the compressor. In such event the valve 21 is closed to cut off communication between the coil and the charging header 8. Also the valve 31 is operated to establish communication be-

tween the return pipe 18 and the header 30 while cutting off communication between the pipe 18 and the suction header. The valve 35 is closed and the valve 36 operated to establish communication between the pipe 32 and the pipe 20 leading to the suction side of the compressor while cutting off communication between the compressor and the suction header 19. Thus the compressor operates to pump out or exhaust the refrigerant from the coil 15 which has been connected to the header 30, the other coils remaining idle during this operation. Pumping out requires only a short time inasmuch as the full suction effort of the compressor is concentrated on the coil whose valves 21 and 31 have been operated. To resume normal operation of the other coils, after pumping out has been completed, it is merely necessary to operate valve 36 to connect the compressor to the suction header 19, the pumped out coil being thereby disconnected from the rest of this system.

It will be understood that while I have herein shown manually operable valves 21 for cutting off several coils as desired, temperature responsive shut off valves such as are well known in the art may be employed for this purpose if desired.

Also it will be understood that the invention is not limited to use in coolers where the surrounding medium to be cooled is air, but that it is equally applicable to use where the medium to be cooled is of a different form such, for example, as brine.

I claim as my invention:

1. A refrigeration system comprising, in combination, a compressor, a condenser into which the compressor discharges, a pipe line leading from the condenser, a charging header, an automatic expansion valve controlling communication between the pipe line and the charging header and operating to maintain a reduced substantially constant pressure in the charging header, a plurality of refrigerating coils connected with the charging header and with the suction side of said compressor, and a valve for each of said coils adapted to feed refrigerant from the charging header to the respective coils, said valve having temperature responsive means operating automatically to limit the volume supplied to the maximum which the coil is capable of evaporating.

2. In a refrigeration system the combination of a compressor, a condenser, a charging header communicating with the condenser and a suction header communicating with the compressor, a plurality of coils connected to said headers in parallel arrangement, a primary expansion valve operating automatically to maintain in the charging header a supply of refrigerant at a substantially constant pressure, and means including a temperature responsive valve

operating automatically to control the volume of refrigerant supplied to the individual coils from the charging header in accordance with the maximum which such coil is capable of evaporating.

70

3. In a refrigeration system, the combination of a compressor and a condenser, a charging header communicating with the condenser, a suction header communicating with the compressor, a plurality of coils each having a supply pipe connected with the charging header and a return pipe connected with the suction header, means for maintaining in the charging header a reduced substantially constant pressure and a control valve for each coil comprising a casing having a valve-controlled passage interposed in said supply line and a second passage interposed in the return pipe, and means in the casing responsive to the temperature of the refrigerant passing through the second mentioned passage for operating said valve whereby to control the volume of refrigerant supplied to the corresponding coil.

80

4. A refrigeration system comprising, in combination, a compressor having a suction line and a discharge line with a condenser therein, a charging header in communication with said condenser, a suction header in communication with said suction line, a plurality of refrigerating coils connected at their opposite ends with said charging and suction headers respectively, and a third header in valve-controlled communication with the return side of each of said coils and with either said suction line or said discharge line at a point between the condenser and compressor.

95

5. A refrigeration system comprising, in combination, a compressor, a condenser, a high pressure line connecting said compressor and condenser, a suction header leading to said compressor, a charging header leading from said condenser, an expansion valve located between said condenser and charging header and operating automatically to maintain a reduced substantially constant pressure in said charging header, a plurality of refrigerating coils connected to said charging header and suction header, a valve for each of said coils regulating the flow of refrigerant in accordance with the refrigerating requirements of its coil, and valve-controlled means for connecting said high pressure line to the return side of said coils independently, whereby to pass hot gas from said high pressure line through the selected coil reversely into said charging header.

105

6. A refrigeration system comprising, in combination, a compressor supplying hot refrigerant at high pressure, a condenser in communication with said compressor, a feed line leading from said condenser, an auto-

110

115

120

125

130

matic expansion valve in said feed line operating to supply refrigerant at a constant pressure substantially below the compressor pressure, a plurality of refrigerating coils, 5 temperature responsive valves operating to control the flow of refrigerant from said feed line to each of said coils, and means for connecting the discharge side of said compressor to the outlet of any of said coils 10 whereby to force hot compressed refrigerant reversely through the selected coil into said feed line.

7. A refrigeration apparatus comprising, in combination, a compressor, a refrigerant 15 circulating system connected with the discharge and suction sides of the compressor and having interposed therein means for cooling the refrigerant discharged from the compressor, an expansion coil interposed in 20 the circulating system, a constant pressure expansion valve operating automatically to reduce the pressure of the cooled refrigerant to be supplied to said coil, and means interposed in the feeding and return sides of said 25 system responsive to the temperature of the refrigerant returning to the compressor and operating to control the volume of refrigerant supplied to said coil.

8. In refrigeration apparatus, the combination of a circulatory system including a 30 compressor and a condenser, a plurality of coils connected in said system, an expansion valve operating automatically to maintain a supply of refrigerant available to all of 35 said coils but at a reduced substantially constant pressure, and valve means controlled by the temperature of the refrigerant returning to the low pressure side of the system for further governing the flow of refrigerant to said coils.

9. A refrigerating system having, in combination, a compressor having a suction line and a discharge line with a condenser there-

in, a plurality of coils connected in parallel between said suction and discharge lines, 45 valve means for disconnecting said coils from the discharge line, a conductor, a single valve for each coil adapted to establish communication between the return side of the coil and either the conductor or the suction 50 line selectively, and valve-controlled means for establishing communication between suction side of said compressor and either the suction line or the conductor.

10. A refrigeration apparatus comprising, 55 in combination, a compressor, a refrigerant circulating system connected with the discharge and suction sides of the compressor and having interposed therein means for cooling the refrigerant discharge from the 60 compressor, an expansion element interposed in the circulating system, an automatic constant pressure reducing valve operating to maintain a supply of refrigerant available to said expansion element at a reduced sub- 65 stantially constant pressure, and valve means controlled by the temperature of the refrigerant returning to the low pressure side of the system for further regulating the flow of refrigerant to said expansion element. 70

11. The method of operating a refrigeration system of the direct expansion type which consists in maintaining a supply of cooled refrigerant at a substantially constant pressure substantially lower than condenser pressure, and discharging the refrigerant from such source of supply into an expansion element such as a coil while regulating the flow of the refrigerant to the coil to the maximum which the coil can 75 evaporate as determined by the temperature of the refrigerant returning from the coil.

In testimony whereof, I have hereunto affixed my signature.

GEORGE HILGER.
